United States Patent Office.

A. H. BAILY AND WILLIAM G. BRATTON, OF MARSEILLES, ILLINOIS.

Letters Patent No. 98,906, dated January 18, 1870.

IMPROVED LEATHER-CHANNELLING AND FOLDING TOOL.

The Schedule referred to in these Letters Patent and making part of the same

To all whom it may concern:

Be it known that we, A. H. BAILY and WILLIAM G. BRATTON, both of Marseilles, in the county of La Salle, in the State of Illinois, have invented a new and improved Channelling and Folding-Tool; and we do hereby declare that the following is a full, clear, and exact description thereof, which will enable others skilled in the art to make and use the same, reference being had to the accompanying drawings, forming part of this specification, in which—

Figures 1 and 2 are plane views.

Figure 3 is a section, through *a b*, fig. 2.

Figures 4, 5, and 6, are plane views of a detail.

This invention relates to a new and useful tool, whereby the style of harness-work known as "rounding," is greatly facilitated and accelerated.

In order to "round" up a strap of leather in the shape it is often used for rein-lines, traces, or other lines about a harness, it is necessary to first cut a channel into each border of the strap, into which the stitches are made, and which, in closing over the seam, hide it, and thus give the work a neat appearance.

After cutting the channels, the strap has to be bent or folded, in order to bring it into proper shape to receive the seam.

To perform these two operations, preparatory to sewing, to wit, channelling and folding, our new tool is intended.

We construct, of brass or iron, a frame-piece, A, with four slots, which guide the piece B, figs. 4, 5, and 6.

This piece B has at one end the two cutters *c c*, which have slots in them, to regulate the depth of the channel.

At the other end of the piece B, a screw, C, enters into it.

This screw C projects through the plate D, and is turned into the shape of a crank.

Its object is to bring the cutters *c c* up or down, according to the width of the strap which is to be rounded.

A hinged arm, E, having on its end a wheel, F, is adapted inside the frame A, and hinged at *d*.

This wheel F swings out and in, as marked by the lines in red.

A shank, G, at the bottom of the frame A, is intended to be held in a vise or inserted into a hole in a bench.

The operation of this tool is as follows:

The strap to be rounded is inserted by one end into the frame A, doubling up under each side of the wheel F, fig. 1.

The piece B is then screwed down until its lower ends touch the edges of the folded strap, the cutters *c c* being set to the proper depth; the strap is then pulled through in the direction of the arrow, fig. 1.

The object of the hinged arm E and wheel F is to allow the wheel to be taken out of the frame A when the end of the strap is inserted, after which it is pushed in again, and the action of pulling the strap through keeps the wheel in its place. It helps to fold the strap by holding it down in the middle, and prevents any irregularities that might happen without it.

What we claim as our invention, and desire to secure by Letters Patent, is—

1. The frame A and piece B, in combination with the cutters *c c*, for cutting channels in a strap, substantially as described.

2. The arm E and wheel F, in combination with the frame A, for folding a strap, and regulating the cutting of the channels, substantially as described.

A. H. BAILY.
WILL. G. BRATTON.
